UNITED STATES PATENT OFFICE.

BENJAMIN DAY, OF WEST HOBOKEN, NEW JERSEY.

MICROMETRICAL ADJUSTMENT FOR PRINTING-FILM FRAMES.

No. 813,867.

Specification of Letters Patent.

Patented Feb. 27, 1906.

Application filed April 26, 1905. Serial No. 257,482.

To all whom it may concern:

Be it known that I, BENJAMIN DAY, a citizen of the United States, and a resident of West Hoboken, in the county of Hudson and 5 State of New Jersey, have invented a new and Improved Micrometrical Adjustment for Printing-Film Frames, of which the following is a full, clear, and exact description.

My invention relates to the accurate hinging and holding of a printing-film frame and its printing-film so that they can be raised, lowered, removed for inking, and replaced and yet fall on the work in exactly their original positions, also to devices whereby subsequent prints from the same printing-film 15 printed over or alongside the first print can be manipulated with accuracy and the manipulation recorded for future reference.

My invention further relates to certain details of construction whereby the necessary accuracy of adjustment is secured quickly and by comparatively simple movements of the parts.

Reference is to be had to the accompanying drawings, forming a part of this specification, in which similar characters of reference indicate corresponding parts in all the figures.

Figure 1 is a fragmentary plan view showing a printing-film frame mounted and ready for use, together with its supporting parts. Fig. 2 is an enlarged vertical section upon the line 2 2 of Fig. 1 looking in the direction of the arrow, showing one of the adjustments used for moving printing-film frames in a lateral direction to the rod 11, whereby it is supported in certain positions, and also showing the adjustable pintle for supporting the frame. Fig. 3 is an enlarged vertical section upon the line 3 3 of Fig. 1 looking in the direction of the arrow and showing the means for adjusting the printing-film frame relatively to its bearings in a direction parallel with the general direction of the rod 11. Fig. 4 is an enlarged section upon the line 4 4 of Fig. 1 looking in the direction of the arrow and showing the general manner of mounting the printing-frame relatively to the supporting-rod 11. Fig. 5 is an enlarged section upon the line 5 5 of Fig. 1 looking in the direction of the arrow and showing the clamping mechanism for securing certain movable parts rigidly upon the rod 11. Fig. 6 is an enlarged detail section upon the line 6 of Fig. 1 looking in the direction of the arrow and showing a part of the means for mounting the pintle 40. Fig. 7 is a somewhat similar section upon the

line 7 of Fig. 1 and showing the part of the means for mounting the pintle 51. Fig. 8 is an enlarged vertical section upon the line 8 8 of Fig. 3 looking in the direction of the arrow 60 and showing the limiting-stop for the micrometer-screw 41, and Fig. 9 is a section upon the line 9 9 of Fig. 1 looking in the direction of the arrow and showing the non-adjustable spring-pintle mating the adjustable 65 spring-pintle shown in Fig. 3.

A pair of heads 9 are mounted upon side bars 10 10 and preferably integral therewith. A supporting-rod 11 is connected with the heads 9 by means of screws 12 and is rigid 70 relatively to the bars 10. A pair of sleeves 13 are each provided with bearings 14 15 and are slidably mounted upon the supporting-rod 11. A casing 16 is provided with a lid 17, secured thereto by means of screws 18, 75 for the purpose of rendering the parts dust-proof and also to protect them in other respects as much as possible. A revolute stub-shaft 19 (see Fig. 2) is fitted with a collar 20, secured rigidly thereto by means of a 80 key 20^a. This stub-shaft is provided with a milled head 22, whereby it may be turned by hand, and adjacent to the milled head 22 is a protractor or micrometer gage 21 with lined index 21^a for indicating the relative angular 85 movements made by the stub-shaft 19 and the milled head 22, and consequently indicating the travel micrometrically of the stub-shaft 19 in the general longitudinal direction of its axis.

Mounted within the casing 16 is a carriage 23, provided with oppositely-disposed portions 24, mating each other and separated by a slot 25 and provided with dependent lugs 23^a 23^b and sliding bearings 23^c and 23^d, fitted to the casing 16 to prevent the carriage from rotating when the milled head 22 is turned to impart motion to it. The bearing 23^d is slotted also to receive the upright boss of the pintle 40, in which slot it enters, as will 90 be understood from Figs. 2 and 5. The oppositely-disposed portions 24 are each threaded internally at 26 and fit a threaded portion 27 of the revolute shaft 19. By turning the milled head 22 the threaded portion 27 of the 95 stub-shaft causes the carriage to travel slowly in the general direction of the axis of the stub-shaft. A powerful spiral spring 28 encircles a part of the stub-shaft 19 and bears against the casing 16 and also against the 100 portions 24 of the carriage. In this way all play as between the stub-shaft 19, the car-

riage 24, the casing 16, and the collar 20, keyed at 20^a, is taken up, for the reason that no matter what position may be assumed by the stub-shaft 19 it is always under more or 5 less tension from the spring 28, and consequently must make a neat fit relatively to the carriage 23, so that the position of the latter is rendered very exact.

The sleeve 13 (see Fig. 5) is provided with 10 a hollow portion 29, threaded internally and fitted with a revolvable cap 30, provided with a neck 31, threaded externally for the purpose. Passing vertically through this cap is a clamping-screw 32, provided with a milled head 33, whereby it may be turned by hand. Disposed vertically and in alinement with the clamping-screw 32 is a dolly 34, encircled by a spiral spring 35 and provided with a head 36, which serves as a limiting-stop for 15 the spiral spring. When the milled head 33 is rotated in one direction, the dolly is forced into firm engagement with the rod 11, thereby clamping the casing 16 and the sleeve 13 firmly in relation to the rod 11, and when the 20 milled head 33 is rotated in the opposite direction the tension of the spring 35 causes the dolly to clear the rod 11, so as to leave the casing free to move relatively upon the same. By this means I avoid any sort of dragging 25 contact as between the clamping-screw 32 and the rod 11 and also avoid any necessity for a rotating member to engage the rod 11.

It will be noted that the two bearings 14 15 are substantially stirrup-shaped and that the 30 dolly 34 is intermediate of these bearings. The result is a triple grip, the dolly 34 pressing the rod 11 in one direction, the bearings 14 15 pressing it in the opposite direction. The clamping effect thus attained is such 35 as to secure the casing 16 upon the rod 11 so firmly that it is to all intents and purposes temporarily integral therewith and yet may be completely released and rendered quite loose thereon by a simple turn of the milled 40 head 33.

It will be noted that the sleeves 13 (see Fig. 1) being revolvable on the rod 11 enables the operator to adjust the film-frame level to the level of the surface on which it is superimposed with great nicety by simply rotating the sleeves and clamping the same in position, this position being shown in Fig. 4.

A pintle 40 of the carriage 23 is provided with a conical point 40^a and with a flat portion 40^b. Encircling this pintle 40 is a washer 37, which bears against a pin 38, passing diametrically through the pintle. The carriage 23 is provided with depending lugs 23^a 23^b and with bearing-lugs 23^c 23^d. The depending lugs 23^a 23^b support the pintle 40, the pintle passing directly through these lugs. A spiral spring 39 bears against the washer 37 on the one side and against the depending lug 23^a on its inner side. The 65 pintle 40 is threaded at its outer end, as indi-

cated in Fig. 3, and fitted with a revolvable milled head 41, threaded internally for the purpose, and provided with a protractor 41^a for determining the relative position of the milled head 41, and consequently of the pintle 40. The milled head 41 is further provided with an annular passage 42, and within this passage is a boss 43, mounted rigidly upon the depending lug 23^a, as shown more particularly in Fig. 3. A screw 44 passes directly through the milled head 41 and is carried bodily around when the milled head is turned. The boss 43 is disposed directly within the orbit of the screw 44, and thus forms a limiting-stop therefor, so that the 70 milled head 41 can only make a single revolution in either direction. The result is that the play of the pintle 40 in the general direction of the axis of the pintle is limited to the distance between two consecutive threads as 75 engaged by the milled head 41. This confines the tension of the spiral spring to a point where it exerts its greatest power and prevents excessive turning of the milled head 41. It therefore follows that no movement given to the spiral spring can materially alter its degree of tension, which thus remains approximately constant. The pintle 40 is further provided with a boss 45, projecting upwardly therefrom, and upon opposite sides of the boss 45 are comparatively small lugs 46, which prevent angular movement of the boss. A set-screw 47, revolvably mounted within the depending lug 23^b, by engaging the flattened portion 40^b of the pintle 80 40 also serves to still further prevent the latter from undergoing any angular movement, so that its position is assured, as well as the accuracy of the movement of the pintle-wheel 41. The set-screw 47 does not bind rigidly 85 upon the pintle 40, however, but merely serves as a neat guide for preventing it from turning or from being displaced in any angular direction. In other words, this screw 47 coacts with the boss 45 to prevent the pintle 90 40 from turning and from moving laterally, but leaves it free to move in the general direction of its axis when actuated by movements of the milled head 41. A pintle 51 (see Fig. 9) is provided with a washer 37^a, 95 similar to the washer 37 in the pintle 40, and is also encircled with a spiral spring 39^a, bearing against a stud 49^a (on its inner left-hand side) and against the washer 37^a. A stop-nut 50, keyed upon the pintle 51, prevents the pintle from being shot out of its bearings by the spiral spring and regulates the tension of the spring. A set-screw 51^a enters the right-hand stud 49^b and bears upon the pintle near the conical end 48 and 100 serves, as the case may be, to either secure the pintle in a fixed position or to take up any slight wear of the pintle or its journal at this point. The pintle 51 is provided with a conical end 48, analogous to the end 43 of the 105

pintle 40. Hinge members 52 are connected with the printing-film frame 53 by means of clamping-jaws 54, held in position by manually-operated fastenings 55. The printing-film is shown at 56 and is supported by the frame 53. A table is represented by dotted lines at 57 in Fig. 4, and upon this table is a block of stone 58 or other member, upon the top of which the design carried by the printing-film is to be printed.

The angular position of each casing 16 is indicated by the two lines 17^a 17^b, which may be brought into or thrown out of registry with each other by slightly turning the milled heads 22 in Fig. 1.

The operation of my device it as follows: The operator selects a printing-film frame 53, (see Fig. 1,) on which is mounted a printing-film 56, provided with, we will say, a stipple of dots in relief. He then secures the hinge members 52 to the corners of the printing-film frame by the device provided therefore by turning the fastenings 55, which jam the clamping-jaws 54 against the inner edge 25 of the frame, holding these hinge members 52 firmly against its outside edge. When both corners of the film-frame are thus clamped, he lays the uninked printing-film level with the surface on which the printing is to be 30 done and in the place it is to occupy on the drawing. He then revolves the sleeve 13 of the left-hand adjuster forward or backward until the cone of the pintle is in line with the socket of the hinge members 52 of the left-hand clamp and slides 13 along the rod 11 until the pintle engages the hinge members 52. He then secures the sleeve in its place by turning the clamping-screw 33, which jams the 35 dolly 34 against the rod 11 and holds the sleeve thereupon. (See Fig. 5.) The left-hand adjuster being thus alined and secured, the right-hand adjuster is then operated in a similar manner—that is to say, the sleeve 13 is moved upward or downward and longitudinally with the rod 11 until the pintle enters the socket of the right-hand clamp in a line with the adjusted left-hand clamp. The pintle 51 is spring-tensioned, so that when the 40 film-frame and its clamps are pushed against its conical point the pintle yields and is carried back by the pressure against the spring until sufficient tension is obtained to hold the printing-film frame and its clamp firmly, yet 45 yieldingly, between the fixed right-hand pintle and the yielding left-hand pintle. It will be then found that the frame and its film is hinged and adjusted to the level of the surface on which it is desired to print and that the film and its frame can be removed, inked, 50 replaced, and printed from many times without alteration of the character or looks of the engraved design on the film; but as the object of my invention is to change materially the character of a stipple or other texture 55 and to record such changes accurately, so that

the operation can be repeated, I will now describe how these changes are brought about. We will say that it is desired to change a stipple of dots into a stipple composed of short perpendicular lines. To do this, I 70 make the first print giving the face value of the texture on the printing-film. I then remove the film, reink, and replace it over the previous print; but before printing the second impression I revolve the milled head 22 (see 75 Fig. 1) on the right and left hand adjusters and turn the said milled head 22 to the right, on each—say, two notches—thus bringing the carriage 23 forward and parallel with the supporting-rod 11 and shifting the printing-film 80 toward the operator just enough to slightly lengthen the dot. When the second print is made, a third and a fourth print will continue to lengthen the dot as long as the film is moved in the same direction by turning the 85 milled head 22 on each adjuster. On the contrary, suppose I wish to make of the dots short lines parallel with the rod 11. In this case I turn the milled head 41 (see Fig. 3) to the right, which causes the pintle to recede, 90 and the tension of the spring to the left-hand adjuster attached to the pintle 51 pushes that pintle to the right, and with it the printing-film frame, and throws it laterally out of register. In both these movements the powerful spiral springs bearing in the casing 16 against said casing and against the carriage 24, Fig. 1, bring the threads of the stub-shaft 19 and the internal threads of the carriage 26 into close contact and prevent any 95 backlash when the milled head 22 is turned in opposite directions. The strain caused by the spring 28 bears not only on the carriage, but on the stub-shaft 19 and on the collar 20, secured to the stub-shaft 19, for if 100 this collar were removed the spring would force the stub-shaft out of its bearing at 16, the strain then being against this collar 16, and when the stub-shaft 19 is turned by the milled head 22 the collar bears firmly against 105 the casing 16, and the threads of the stub-shaft at 27 are forced against the internal threading of the carriage 23 at the threaded part 26. In Fig. 3 the same principle is carried out. The pintle 40 is collared at 37 and the collar held by a pin 38. A powerful spiral spring 39 would force the pintle out of its bearings at 23^a were it not for its being held by the internally-threaded milled head 41, holding it by means of the threaded portion 110 of the pintle 40. The strain of the spiral spring 39 bearing against the lug 23^a and against the collar 37, held by the pin 38, draws the milled head 41 firmly against the lug 23^a and takes up the backlash of the threaded part of the 115 milled head 41 when revolved on the threaded portion of the pintle 40. The boss 45 is comparatively long, so that a comparatively slight movement of the upper or outer end indicates a much smaller rocking movement 120

upon the part of the pintle. In other words, an imperceptible movement of the pintle is readily detected by the operator.

5 While, as shown, I support the printing-frame by means of pintles and sockets, I do not limit myself to this exact construction, as other bearings may be substituted for supporting the frame without departing from the spirit of my invention.

10 Having thus described my invention, I claim as new and desire to secure by Letters Patent—

15 1. The combination of a locally-threaded stub-shaft journaled in a casing at both ends with a revoluble milled protractor operating or turning said stub-shaft at one end and a fixed collar at the other end to hold said stub-shaft loosely in position, an internally-threaded carriage through which the threaded 20 portion of said stub-shaft passes, fitting its threads easily, and a powerful spiral spring encircling one end of the stub-shaft and tensioning the threads of the carriage against the threads of the stub-shaft and likewise of the 25 collar where it bears on the outside of the casing, thus bringing pressure to bear on the threads of the carriage so as to take up the backlash of the threads when the stub-shaft is rotated and at the bearings of the collar 30 where it impinges on the outside of the casing.

35 2. The combination of a milled-head protractor provided with an annular passage, a boss entering this annular passage and rigidly mounted upon the stud against which the milled-head protractor revolves, and a screw passing directly through the milled-head protractor and into this annular passage, which, when the milled-head protractor is 40 turned in either direction the movement of the threaded pintle, is stopped by the screw striking the boss.

45 3. The combination of a casing, a carriage movably mounted therein and provided with a thread, a revoluble stub-shaft mounted partially within said casing and provided with a thread engaging said thread of said carriage, means for turning said revoluble stub-shaft, a spring mounted within said casing and engaging said carriage for the purpose of tensioning the same relatively to said stub-shaft, and means connected with said carriage for supporting a frame.

55 4. The combination of a supporting-rod, a sleeve mounted thereupon, a dolly connected with said sleeve, a spring for tensioning said dolly, and a screw for forcing said dolly into engagement with said supporting-rod.

60 5. The combination of a casing, a carriage mounted therein, a pintle engaging said carriage and adjustable relatively thereto, a spring for tensioning said pintle relatively to said carriage, a lug mounted upon said carriage, a protractor for measuring movements 65 of said pintle relatively to said carriage, said

protractor being provided with a revoluble head, and a member mounted upon said revoluble head and adapted to engage said lug.

6. The combination of a pintle serving as a journal for supporting an angularly-movable 70 frame, a carriage provided with a lug for supporting said pintle, a spring for tensioning said pintle relatively to said carriage, a protractor provided with a revoluble member for adjusting the position of said pintle relatively to said carriage, and means for limiting the range of said protractor so as to maintain the tension of said spring approximately constant.

7. The combination of a casing, a stub-shaft mounted therein and adapted to be rotated, said stub-shaft being provided with a thread, a collar mounted upon said stub-shaft and engaging said casing so as to prevent longitudinal movements of said stub-shaft in 85 one direction, a carriage mounted within said casing and provided with a thread engaging said thread of said stub-shaft, said casing being thus rendered movable by rotation of said stub-shaft, a spring encircling said stub-shaft 90 and engaging said casing and said carriage, and a bearing connected with said carriage for supporting a printing-film.

8. The combination of a pintle, one end of which is threaded, a collar mounted upon 95 said pintle, a comparatively strong spiral spring encircling said pintle and bearing at one end of said spring against said collar, a stop for supporting the other end of said spring, a revoluble milled-head protractor 100 threaded internally to fit the threaded end of said pintle and bearing against said stop, a longitudinal guide-boss attached to said pintle and radiating laterally therefrom, and means for preventing angular movement of 105 said guide-boss.

9. The combination of a frame for supporting a printing-film or the like, a pintle for supporting said frame, a boss mounted upon said pintle and extending radially therefrom 110 to prevent rotation thereof, guide mechanism engaging said boss and allowing the same to travel in the general longitudinal direction of said pintle but not to move angularly, and a micrometrical adjusting device for moving 115 said pintle in the general direction of its axis, thereby securing a fine adjustment.

10. The combination of a supporting-rod, a casing mounted thereupon, a sleeve slidably mounted within said casing, a screw connected 120 with said sleeve and adapted to move toward and from said supporting-rod, a dolly mounted intermediate of said screw and said rod so as to be forced against the latter, and mechanism connected with said casing for supporting a frame.

11. The combination of a carriage provided with depending lugs having apertures therethrough, a pintle disposed loosely within said apertures and provided with a threaded 130

- end, a revolute member mounted upon said pintle and provided with a thread engaging said thread of said pintle for causing said pintle to travel in the general longitudinal direction of its axis relatively to said carriage, and a longitudinal guide-boss mounted upon said pintle and projecting laterally therefrom, for the purpose of engaging a portion of said carriage serving as a guideway therefor.
12. The combination of a carriage provided with a guideway, a pintle supported by said carriage and provided with a journal for supporting a printing-film frame or the like, a boss mounted upon said pintle and projecting laterally therefrom into said guideway so as to prevent rotation of said pintle and yet to move freely in the general longitudinal direction of said pintle, micrometric mechanism for moving said pintle in the general direction of the length thereof, and means for supporting said carriage.
13. The combination of a casing, a stub-shaft revolvably journaled therein and having a comparatively loose bearing-contact therewith, said stub-shaft being provided with a thread, a collar mounted upon said stub-shaft and engaging said casing so as to prevent movements of said stub-shaft in the general direction of the length of the axis thereof, a carriage mounted within said casing and provided with a thread engaging said thread of said stub-shaft, a spring for tensioning said stub-shaft relatively to said casing so as to limit the main friction due to rotation of said stub-shaft to points of engagement only, and a bearing connected with

said carriage for supporting a printing-film or the like.

14. The combination of a casing, a carriage movable relatively thereto and provided with a thread, a stub-shaft provided with a thread engaging said thread of said carriage, a collar mounted upon said stub-shaft and engaging said casing, a spring engaging said casing and said carriage so as to take up the play between said stub-shaft and said carriage, a bearing connected with said carriage and adapted to support a printing-film frame or the like, and a member connected with said stub-shaft whereby the latter may be rotated.

15. The combination of a supporting member provided with an aperture, a pintle mounted upon said supporting member and adapted to move relatively thereto for supporting a printing-film frame or the like, a boss mounted upon said pintle and projecting radially therefrom through said aperture in said supporting member to prevent said pintle from turning, said boss being comparatively long so that its outer end may be readily observed by the operator, and a revolute member threaded upon said pintle and engaging said carriage for adjusting said pintle in the general direction of the axis thereof.

In testimony whereof I have signed my name to this specification in the presence of two subscribing witnesses.

BENJAMIN DAY.
